AIR COMB

Humphrey J. Lynch, Oakland, Calif.

Application July 6, 1936, Serial No. 88,947

2 Claims. (Cl. 132—13)

This invention relates to combs used in the treatment of the hair, and particularly to a comb which will also provide for treatment of the scalp during the operation of combing the hair.

The principal object of the invention is to provide a comb which will simultaneously comb the hair, and apply a fluid to the hair or scalp.

A further object of the invention is to provide a device of the character described in which the direction of flow of the fluid may be selectively changed so that matter may be applied to the hair or scalp, or withdrawn therefrom.

The invention possesses other objects, and features of value, some of which together with the foregoing will be specifically set forth in the specification hereunto annexed. It is to be understood that the invention is not to be limited to that form thereof shown and described, as various embodiments thereof may be employed within the scope of the appended claims.

The figure of the drawing is a side elevational view of the hair comb and its associated apparatus, portions of the view being broken away to more clearly disclose the construction.

In detail, the invention comprises a comb C provided with a cylindrical hollow back 1, spaced longitudinally on which is provided a plurality of teeth 2 each of which is hollow, in communication with the interior of the back 1, and open to provide a discharge orifice at its distal end. One end of the back 1 is closed and the other end projects slightly to provide for the attachment thereto of one end of a flexible conduit 3, the other end of the conduit being attached to the tangentially extending nipple of a pump casing 4. The conduit 3 is shown broken off in the illustration, it of course being evident that this was done to conserve space in the drawing as the conduit may be made as long or as short as desired. Mounted in the pump casing 4 is a suitable vaned rotor adapted to be rotated at high speed by a reversible motor 5 provided with a handle 6 attached to and extending therefrom; and mounted in the outer end of the handle is a suitable reversing switch 7 which controls the current flow to the motor through the supply leads 8 which may, of course, be attached to a suitable source of electric current.

In operation, when the motor 5 is driving the rotor within the pump casing 4, a current of air will be forced through the conduit 3, the hollow back of the comb C and out through the apertured ends of the teeth 2. It will be seen that when the comb is moved through the hair, the

air discharged from the teeth will be distributed through the hair and against the scalp thereby blowing out any dust or dandruff that may be present in the hair or on the scalp and providing a very beneficial aeration treatment for the hair.

It will be obvious that if the direction of rotation of the motor 5 is reversed the flow of air through the conduit 3 will be reversed, thereby creating a suction at each of the orifices of the teeth and drawing any dust or other matter into the conduit from which it will be discharged through the open port of the pump 4. The current of air entering the hair from the atmosphere surrounding the head, due to the reduced pressure created at the roots of the hair by the reversed direction of flow of air through the comb teeth, will be sufficient to dislodge any foreign matter which may be present in the hair.

It will be obvious that the comb is not limited to the application, to the hair or scalp, of air only, since, by holding the inlet of the pump casing adjacent a jet of steam or other vapor, these latter may be forced through the system and discharged from the orifices of the teeth.

Another method of operating the apparatus is to immerse the comb C in a container of fluid, operate the motor 5 for a short interval to create suction in the system to draw some of the fluid into the comb and conduit 3, and then cause discharge of the fluid from the teeth 2 by reversing the motor to create a reversal of flow of the fluid, this of course being done after the comb has been placed in the hair.

I claim:

1. The combination of a comb having a recessed back, teeth secured in spaced relation to said back, each of said teeth being hollow and provided at its end with an orifice in communication with the recess of said back, a flexible hollow conduit secured at one end thereof to said back, the interior of said conduit being in communication with the recess of said back, a hollow casing having a discharge port therein connected with the other end of said conduit with the interiors of said conduit and casing in communication, a fluid-impelling rotor rotatably mounted in said casing, and means for selectively rotating said rotor in different directions to institute flows of fluid in different directions through said conduit.

2. The combination of a comb having a recessed back, teeth secured in spaced relation to said back, each of said teeth being hollow and provided at its end with an orifice in communi-

cation with the recess of said back, a flexible hollow conduit secured at one end thereof to said back, the interior of said conduit being in communication with the recess of said back, a hollow casing having a discharge port therein connected with the other end of said conduit with the interiors of said conduit and casing in communication, a fluid-impelling rotor rotatably mounted in said casing, a reversible motor oper-

atively connected with said rotor, a handle carried by said motor, current conducting leads for supplying electric current from a source of current to said motor, and a switch connected with said leads for reversing the current flow therethrough to selectively vary the direction of rotation of said motor. 5

HUMPHREY J. LYNCH.
